(57) **CLAIM**

The ornamental design for a truck cradle assembly, as shown and described.

DESCRIPTION

FIG. 1 is a top, front left side perspective view of a truck cradle assembly showing my new design;

FIG. 2 is a front elevation view;

FIG. 3 is a rear elevation view;

FIG. 4 is a right side elevation view;

FIG. 5 is a top plane view; and,

FIG. 6 is a bottom plane view.

The broken lines are included for the purpose of illustrating environment and forms no part of the claimed design.
